UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,833, dated November 5, 1895.

Application filed September 30, 1895. Serial No. 564,219. Term of patent 3 $\frac{1}{2}$ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

5 The design consists of a series of continuous ornamental scrolls interlacing with a shield-like figure or ornament, as represented in the accompanying drawing.

The border of the design is formed of a

5 large shield-like figure or ornament with ornamental scrolls on each side of said figure

and interlacing with said figure and upright ornaments interlaced with said ornamental scrolls on each side of the shield-like figure, as shown in the drawing.

What I claim is—

1. The design for wall paper herein shown and described.
2. In the design for wall paper, the border herein shown and described.

Witness my hand this 27th day of September, 1895.

CHARLES BOOZ.
